J. HERZOG.

FILING CABINET.

APPLICATION FILED JUNE 17, 1919.

1,392,055.

Patented Sept. 27, 1921.

John Herzog,
by Jacob Schreiter
his Attorney

UNITED STATES PATENT OFFICE.

JOHN HERZOG, OF SAGINAW, MICHIGAN, ASSIGNOR TO SONORA PHONOGRAPH CORPORATION, A CORPORATION OF NEW YORK.

FILING-CABINET.

1,392,055.

Specification of Letters Patent. Patented Sept. 27, 1921.

Application filed June 17, 1919. Serial No. 304,761.

To all whom it may concern:

Be it known that I, JOHN HERZOG, a citizen of the United States, and a resident of the city of Saginaw, county of Saginaw and

5 State of Michigan, United States of America, have invented a certain new and useful Filing-Cabinet, of which the following is a specification.

10 My invention relates to filing cabinets for talking machine disk records, and more particularly to that type of cabinet in which each individual record is carried in an envelop. A plurality of such envelops is carried in a rod in such a manner that each envelop may be separately tilted to give access 15 to the record contained therein. A second rod passes through all of the envelops and acts as a stop to limit the pivotal movement of the envelops.

20 One object of my invention is to provide means whereby the envelops may be removed from the cabinet, or new ones placed therein without dismantling the cabinet.

25 A further object is to provide means whereby the exterior of the cabinet, or the rack carrying the envelops will not be marred by the devices which permit of the removal of the envelops.

30 A further object of the invention is to produce a device of the character described, which is extremely simple in construction, neat and attractive in appearance, thoroughly reliable and efficient in its purpose, and inexpensive to manufacture.

35 With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

40 The inventive idea involved is capable of receiving a variety of mechanical expressions, one of which for the purpose of illustrating the invention, is shown in the accompanying drawings.

45 The invention will be first described in connection with the accompanying drawings, 50 wherein similar reference characters are used

to designate corresponding parts throughout the several views, and then more specifically defined and indicated in the appended claims.

In the drawings,—

55 Figure 1 is a front elevation of a rack for carrying a plurality of envelops, embodying my invention;

Fig. 2 is a section on the line 2—2 of Fig. 1, looking in the direction of the arrow;

Fig. 3 is an enlarged detail section on the plane indicated by the line 3—3 of Fig. 4;

Fig. 4 is a horizontal section on the line 4—4 of Fig. 3;

Fig. 5 is a side elevation of a clip;

Fig. 6 is a detail view of a portion of the device.

65 In carrying out my invention, I provide a rack comprising a top member 1, a bottom member 2, and side members 3 and 4. A central partition 5 is employed, and between the partition 5 and the sides 3 and 4 are partitions 6, 6, by means of which the records may be subdivided into classes.

70 I desire to have it understood that instead of providing a separate rack as above described, the top and bottom members, and the partitions, may be secured in the talking machine cabinet, in which case the side walls 80 of the cabinet will take the place of the members 3 and 4.

75 Carried on the inside of each side member, at the lower front side thereof, is a clip 7. The clips are formed of sheet metal, and 85 each is provided with a pair of keyholes 8. The smaller end of each keyhole is counter-bored for the reception of the head 9 of a screw 10, by means of which the clips are secured in place.

80 One side of the clip is offset as at 11, and there are two open slots 12, and 13, in the offset portion. The slots are in alignment with perforations 14 and 15, in the central partition 5.

85 Carried in the slots 12 and the perforations 14, is a pivoted rod composed of two sections 16 and 17; and a stop rod composed of two sections 18 and 19 is carried in the slots 13 and perforation 15.

90

95

100

Each envelop has at its lower front corner a perforation 20, by means of which the envelops are mounted on the pivot rod 16, 17, and the stop rod 18, 19, passes through 5 a segmental slot 21 in each envelop.

The pivot and stop rods are loosely carried in the perforations of the partition, and the slots 12 and 13. When it is desired to remove an envelop, the screws 10 are 10 loosened, the clip 7 is moved forward until the heads 9 of the screws are opposite the enlargements of the keyholes. The clip may then be removed as the rods are free of the slots 12 and 13. The ends of the rod sections 15 may now be removed from the openings or bearings in the partitions 5, and all of the envelops on those rod sections may be removed bodily from the rack.

The screws will remain in the side members 3 and 4, and there will be no danger of 20 their becoming lost or mislaid.

The envelops may be replaced in the rack by reversing the above described operation.

When the device is in actual use, the rods 25 16, 17, 18, and 19, are prevented from slipping out of the open slots 12 and 13, as the members 6 are provided at their lower extremity with a cut-away portion, so that these members 6 fit almost directly behind 30 the rods, and thus prevent backward motion. This is clearly illustrated in Fig. 1, as the members 6 are shown in dotted lines, where the rods pass in front thereof.

In accordance with the provisions of the 35 patent statute, I have described the principle of my invention together with the apparatus which I now consider to represent the best embodiment thereof, but I desire it understood that my invention is not confined to 40 the particular form of apparatus herein shown and described, the same being merely illustrative, and that the invention can be carried out in other ways without departing from the spirit of my invention, and 45 therefore, I claim broadly the right to employ all equivalent instrumentalities coming within the scope of the appended claims, and by means of which objects of my invention are attained, and the new results 50 accomplished, as herein set forth, as it is obvious that the particular embodiment herein shown and described is only one of many that can be employed to attain these objects and accomplish these results.

Having now described my invention, what 55 I claim and desire to secure by Letters Patent is as follows:

1. A device of the character described, comprising a frame, a clip associated with 60 the frame, a rod engaging the clip, the association between the frame, clip and rod being such that upon a movement of the clip relatively to one of said members, the rod will be released from engagement therewith.

65 2. A device of the character described,

comprising a frame having side members, oppositely disposed clips connected to and between the members, a rod engaging the clips, the connection between the clips and members being constructed and arranged to 70 permit of a relative movement between the clips and the members.

3. A device of the character described, comprising a rectangular frame, having a central partition, there being a perforation 75 in the partition, a rod engaging the partition, a clip carried on the inside of the frame, said clip engaging the rod, and means whereby the clip may be moved relatively to the frame and rod to disengage the clip from 80 the frame and rod.

4. A device of the character described, comprising a frame having side members and a partition between the members, there being a perforation in the partition, a pair 85 of aligned rods, each having one end engaging the perforation, a clip carried on the inside of each side member, the opposite end of each rod engaging a slot in a clip, screws for securing the clips to the members, and means for moving the clips to release the rods.

5. A device of the character described, comprising a frame having side members, oppositely disposed clips associated with the 95 members, rods engaging the clips, a plurality of envelops pivotally carried by the rods, the association between the clips and members being constructed and arranged to permit of a relative movement between the clips and the 100 members to permit of the disengagement of the rods and clips.

6. A device of the character described, comprising a frame having side members and a central partition, there being a plurality 105 of perforations in the partition, a clip carried on the inside of each side member, there being slots in the clip in alignment with the perforations in the partition, a rod engaging a perforation, the opposite end of 110 the rod engaging a slot in a clip, a plurality of envelops pivotally mounted on the rod, each envelop having a segmental slot, a second rod engaging a perforation in the partition, and a slot in the clip, said latter rod 115 passing through the segmental slots in the envelops, each clip having a plurality of keyholes, a screw engaging each keyhole and entering the side member, whereby the clip may be moved to disengage the slots from 120 the rods and the clip from the side members.

7. A device of the character described, comprising a frame having side members and a central partition, there being a plurality 125 of perforations in the partition, a clip carried on the inside of each side member, there being open ended slots in the clip in alignment with the perforations in the partition, a rod engaging a perforation, the opposite end of the rod engaging a slot in 130

a clip, a plurality of envelops pivotally mounted on the rod, each envelop having a segmental slot, a second rod engaging a perforation in the partition and a slot in the 5 clip, said latter rod passing through the segmental slots in the envelops, each clip having a plurality of keyholes, the small end of each keyhole being counterbored to receive the head of a screw whereby the latter 10 will be flush with the surface of the clip, a

screw engaging each keyhole and entering a side member, whereby the clip may be moved to disengage the slots from the rods without removing the screw from the member.

This specification signed and witnessed 15 this 26 day of May, 1919.

JOHN HERZOG.
